UNITED STATES PATENT OFFICE

2,290,322

X-RAY TUBE SAFETY SWITCH

Edwin R. Goldfield, University Heights, Ohio, assignor to Picker X-Ray Corporation, Waite Manufacturing Division, Inc., Cleveland, Ohio, a corporation of Ohio

Application September 27, 1940, Serial No. 358,602

3 Claims. (Cl. 250—103)

This invention relates to improvements in safety devices for preventing the overheating of X-ray tubes, and more particularly to a switch arranged to automatically cut off the tube circuit if the temperature of the tube rises above a predetermined point.

An object of the present invention is to disconnect the tube circuit by means of a device movable in response to tube temperature and which acts automatically so as to be in no way dependent upon the operator. This feature may be combined with a signal device adapted to first signal the operator that excessive heat conditions have arisen so that he may complete the operation in which he is engaged before the automatic device deenergizes the tube. My invention contemplates any means for producing the desired results which comes within the purview of the appended claims but in the embodiment shown herein I have selected a fluid-tight housing for the X-ray tube filled with a fluid which is expandable when heated and have arranged an expandable diaphragm subject to the pressure of the fluid for actuating a switch in the tube control circuit. Other embodiments will occur to those skilled in this art.

In the drawing, Fig. 1 is a central longitudinal section through a typical X-ray tube and housing illustrating one means of practicing my invention; Fig. 2 is an enlarged sectional view of the apparatus at the left-hand end of Fig. 1; Fig. 3 is a plan view on reduced scale of a button retaining cup as viewed from the left-hand end of Fig. 2; while Fig. 4 is a diagrammatic view illustrating the place of my improved safety device in a tube control circuit.

In Fig. 1 I have shown an X-ray tube and its housing such as is disclosed in the copending application of Edward B. Graves, Serial No. 320,323, filed February 23, 1940, but it will be understood that this is in no sense a limitation but merely indicates one manner in which my invention may be applied to an X-ray tube.

In Fig. 1 the tube proper is indicated at 10 having an anode 11 which is connected to terminals 12 and having a cathode, not shown, which is connected to the terminals 13. The tube is encased in a fluid-tight housing 14 having the usual window opening at 15. The housing has tubular extensions 16 for receiving cable connections for the attachment of the energizing circuit to the terminals 12 and 13. As explained in the above mentioned copending application, the housing 14 is filled with an insulating oil or the like which expands and contracts in response to temperature changes within the housing 14. It is usual to provide some sort of expandable diaphragm wall subject to the pressure in the housing which expands as the oil is heated so as to compensate and prevent undesirable rises of pressure within the housing. As shown in the

copending application but having no particular bearing here, I have indicated a fan at 17 driven by a motor 18 which may be used to keep the oil in circulation, as explained in the copending application.

The present invention utilizes the movement of the expandable diaphragm to automatically de-energize the tube upon an undesirable rise of temperature in the tube housing, such as would occur after unusually long or heavy demand upon the X-ray tube or upon some unforeseen failure or the like. My invention provides an automatic means for cutting off the current supply to the X-ray tube when it has generated an undue amount of heat. One embodiment of my invention as here shown makes use of an expandable and contractible bellows 19 such as has heretofore been used merely to compensate for changes in pressure within the housing 14. This bellows 20 as shown in Fig. 2 has its left-hand end secured to the housing 14 and its right-hand end is subjected to the pressure of the oil within the housing so that when the oil expands with a rising temperature, the right-hand end or bellows head 19a moves toward the left so as to contract the bellows. This of course relieves the pressure within the housing and I utilize the movement of this bellows head to actuate a switch device 20 so as to deenergize the tube if the temperature within the housing has increased to an unusual degree.

For purposes of illustration I have used a standard tube circuit as shown in Fig. 4 to indicate one possible position of the switch 20 in such a circuit. The X-ray tube is indicated at 10 with a current supply at L₁, L₂ connected by means of an autotransformer 21 with the primary 22 of the transformer whose secondary 23 supplies high tension current to the tube 10. The filament circuit is indicated at L₃, L₄. The usual disconnect switch is shown at 24 and in series therewith I have indicated the switch 20 which as mentioned before, I operate in response to temperature conditions of the X-ray tube. It will be obvious that when the switch 20 is opened the tube 10 will be deenergized.

Referring back to Fig. 2, I have combined the safety switch with a device adapted to give a preliminary warning signal to the operator before the safety switch opens the tube circuit. In the form here shown a button 25 is movable in and out of an opening in the end of the housing 14. The button has a flange 25a adapted to engage an abutment flange 26 extending inwardly from the end of the tube housing and limiting outward movement of the button. For limiting inward movement of the button I have provided a cup 27, better shown in Fig. 3, which has a central opening 27a through which the switch parts extend but adapted to engage the flange 25a of the button. The cup has a peripheral flange 27b by

which it is held between the bellows and the end of the housing so as to fix the cup in place. A light spring 28 urges the button 25 inwardly. The outer portion of the button surface as indicated at 29 is of white or some other neutral color, whereas a portion of the surface 30 located inwardly therefrom may have a red band upon it so as to provide a warning when the button is moved out of the housing sufficiently to disclose the red band.

The switch 20 is of a known type, operable by means of relative longitudinal movement of the parts thereof, one part being associated with the button 25 and the other part with the bellows head 19a so that when movement of the button 25 outwardly is arrested by engagement of the parts 25a and 26 then further movement of the bellows head 19a toward the left as viewed in Figs. 1 and 2, will take up the lost motion of the switch and eventually throw the switch so as to open the tube circuit.

For purposes of understanding the operation of the present invention, I will explain the operation of the switch which, per se, is not my invention. An outer sleeve 31 carries at its right-hand end a metal housing 32 within which is held a block of insulating material 33 which carries a pair of binding posts 34 located one behind the other in Fig. 2. To these binding posts are connected the wires 22a and 22b, the position of which will be understood from the diagram of Fig. 4. The binding posts 34 are electrically connected with spaced contacts located in the central cavity of the insulating block 33. A roller member 35 is adapted to make connection between these contacts when in the full line position of Fig. 2, whereas in the dot-dash position thereof the contact will be broken through the switch. A yieldable toggle device of known construction is utilized for snapping the contact member 35 over center. The toggle device includes a bell crank arm 36a, the other arm of which is indicated at 36b. The bell crank has a pivot at 37 which is a pin mounted in the sleeve 31. An inner sleeve 38 is reciprocable within the sleeve 31 and carries at its right-hand end a slotted recess within which the arm 36b rests. A spring 39 is engaged between the left-hand end of sleeve 38 and a member 40 which is held in position by the pin 37. Thus the spring 39 tends to move sleeve 38 toward the left so as to normally return the switch parts to the full line position of Fig. 2 when pressure on the diaphragm head 19a is relieved.

The switch 20 may be connected to the diaphragm head in any desired manner. As here shown a plate 41 is connected by a screw 42 with the diaphragm head and a U-shape strap 43 is secured by threaded washers to the outer face of sleeve 31, the sides of the strap extending down to the member 41 on either side of block 33 and the saddle 43 being secured to the member 41.

It results from the above construction that with the parts in the position of Fig. 2, the X-ray tube may be energized by closing the switch 24 because the switch 20 is in normal closed position as shown in full lines in Fig. 2. As the oil in the housing 14 expands with rising temperature of the tube, the diaphragm head 19a moves toward the left pushing the entire switch 20 toward the left because the spring 39 is stronger than the spring 28. The left-hand end of sleeve 38 thus pushes button 25 out of the housing until eventually the red band 30 is visible. This gives the operator warning that the tube is becoming

heated and that undue prolongation of the operation will result in an automatic shutdown. When the flange 26 engages flange 25a, limiting further outward movement of the button 25, further movement of the diaphragm head 19a toward the left causes relative sliding movement of the switch operating sleeves 31 and 38. This carries the bell crank arms 36a and 36b clockwise about the pin 37 until the toggle switch throws over center, moving the roller contact 35 to the dot-dash position of Fig. 2 and opening the switch 20. This deenergizes the tube which must be left idle for a period sufficient to permit the oil to contract within the housing 14 and permitting the diaphragm head 19a to move sufficiently toward the right to again cause the toggle switch to snap over center to the full line position of Fig. 2. In other words there is sufficient lost motion in switch 20 to give a warning period before the switch is opened and then to give a cooling period for the tube of a substantial time period. In other words the device does not flutter back and forth making and breaking the switch contacts rapidly.

It will be noted that the cable 44 housing the wires 22a and 22b is looped through several openings 45 in the cup 27 so as to establish a bight 44a in the cable, allowing for the longitudinal movement of the switch parts at all times.

What I claim is:

1. In the combination of an X-ray and a control circuit therefor, a fluid-tight housing for said tube, fluid in said housing expandable in response to temperature change, an expandable diaphragm movable in response to fluid pressure in said housing, a warning signal device carried by said housing and movable relative thereto firstly to give a signal and secondly to engage an abutment, a switch in said circuit having relatively movable parts for making and breaking the circuit, and one of said parts engaging said signal device and the other of said parts engaging said diaphragm in a manner to operate said switch when said signal device is held by said abutment and said diaphragm continues to move.

2. In the combination of an X-ray tube and a control circuit therefor, a fluid-tight housing for said tube, fluid in said housing expandable in response to temperature change, an expandable diaphragm movable in response to fluid pressure in said housing, a toggle switch in said circuit, relatively movable parts connected with said diaphragm and with said housing respectively, and said parts being operatively connected with said switch to move said toggle over center to make and break said circuit upon relative movement of said parts, whereby when said circuit is broken at said switch, a cooling period is necessary to contract said diaphragm sufficiently to move said toggle over center in switch closing direction.

3. In the combination of an X-ray tube and a control circuit therefor, a part expandable by heat generated by said tube in operation, a switch in said circuit, means operatively connected with said expandable part for controlling said switch including a spring loaded by movement of said expandable part, and said spring having an operative connection for throwing said switch open when said spring is loaded, whereby when said circuit is broken at said switch, a cooling period of said tube is necessary to provide return movement of said expandable part sufficient to permit closing of said switch.
